SLIDING EXTENSIBLE AND CONTRACTIBLE
WINDOW SCREEN

Harry Eli Baumgardner, Yeadon, Pa.

Application June 26, 1934, Serial No. 732,532

3 Claims. (Cl. 156—38)

This invention relates to an improved window screen, which is not only capable of extensibility but also capable of being reduced, thereby varying its size, to allow same to be applied or fit window frames of various sizes, but is also capable of sliding movement in the window frame, and especially when the upper sash is lowered. Another purpose of the invention, is to provide in an extensible window screen, a plurality of telescopic sections, housing a plurality of inner telescopic sections (which carry and support wire fabric screening), the first sections having means for the reception of hangers or brackets carried by the sill and by the lower rail of the upper sash for supporting the window screen in place, and when the hangers at the bottom are disconnected from the sections of the first screen frame, it is possible to adjust the upper sash, in which event the window screen may be adjusted therewith.

It is obvious that by dimensioning the wire fabric screening, it is possible to provide an inner screening supporting frame, to be so supported on the interior of the outer window screen frame, as to allow a minimum reduction in area of the outer screen frame, as well as allowing the outer window screen frame to be extended arealy to a maximum degree, allowing the window screen to be accommodated to various sizes of window frames. By the dimensioning of the various sections of the window screen, inner and outer frames, it is possible to accommodate this window screen to substantially any size of window frames.

It is to be understood that the particulars herein given are in no way limitative, and that while still keeping within the scope of the invention, any desired modification of details and proportions may be made in the construction of the appliance according to circumstances.

The invention comprises further features and combination of parts to be hereinafter set forth, shown in the drawings and claimed.

In the drawings:—

Figure 1 is a view in elevation of the outside of a window frame of substantially maximum size, showing the improved window screen applied and extended to substantially maximum size, to be accommodated in the window frame.

Figure 2 is a view in elevation of the outside of a window frame of substantially minimum size, illustrating a window screen as applied and reduced to a substantially minimum size to be accommodated in said frame.

Figure 3 is an enlarged view in perspective

and partly in section of at least two corners of the window screen, in order to illustrate more in detail the construction thereof.

Figure 4 is a sectional view on line 4—4 of Figure 1.

Figure 5 is a view in perspective of at least two corners of the inner screening carrying and supporting frame.

Figure 6 is an enlarged detail sectional view on line 6—6 of Figure 1 showing the inner screening supporting and carrying frame.

Figure 7 is a view in elevation of the inside screen frame showing the manner of connecting the four corner sections together and illustrating the wire fabric screening.

Figure 8 is a view in elevation showing the window screen as mounted in a casement window frame illustrating the means for holding the window screen in place.

Referring to the drawings 1 identifies the window screen as a whole, and it comprises an inner frame 2 and an outer frame 3. The reason for identifying these frames as inner and outer is that the former is enclosed or encased in the latter.

The outer frame comprises four corner sections 4, 5, 6, and 7, which are hollow and may be constructed of any suitable metal, preferably non-corrosive sheet metal, and the legs of these four corner sections are constructed to telescope, in which event a rectangular frame is caused to be constructed for housing and supporting the inner frame, which carries and supports wire fabric screening 8 of any suitable gauge, preferably of the kind that is used in connection with window screens. The opposed walls 9 have their inner flanged portions 10 rolled into hollow beads 11 which impinge on the wire fabric screening 8.

The four corner sections of this outer frame may be constructed in any sizes, and preferably of such size that when the four corner sections are extended approximately to their maximum positions, the window screen may fit the maximum sizes of window frames, and when adjusted telescopically for a reduction in the area of the screen frame, the window screen may be applied to a minimum size of window frame, therefore in this manner the window screen may fit window frames of various sizes in between the minimum and maximum sizes of window frames.

The inner frame 2, which supports and carries the wire fabric screening likewise consists of four corner sections 12, 13, 14, and 15, which are received in the four corner sections 4, 5, 6, and 7, of the outer frame. These four corner sections 12,

13, 14, and 15 are hollow and have hollow rolled beads 16 and 17, and in order to fasten the wire fabric screening 8 to the four corner sections, while they are in telescopic relation this wire fabric screening on its four edge portions is rolled around on the inside of the hollow beads 16 of said corner sections, as is shown in an enlarged detail sectional view of the inner frame 2. It is by means of the hollow rolled beads 16 and 17 that the four corner sections of the inner frame 2 are telescopically united.

15 Adjacent the lower opposite corners of the outer screen frame as well as adjacent the upper corners of the outer screen frame on the inside thereof hanger plates 19 and 20 are secured in any suitable manner preferably electrically welded or otherwise, and these plates have elongated slots 21 and 22, through which screw eye hangers 23 and 24 engage and are threaded into the sill of the window frame and into the lower rail of the upper sash, for the purpose of anchoring the window screen in place. Obviously upon examining Figure 1 of the drawings it is possible to lower the upper sash, causing the perpendicular legs of the upper corner sections of the outer frame to telescope the perpendicular legs of the lower corner sections, thereby providing a ventilating air space between the upper rail of the upper sash and the upper horizontal rail of the window frame as shown at 25. A small rigid window screen (not shown) may be inserted in said space 25. Also it is obviously possible to restore the upper sash to its normal position as shown in Figure 1, by rendering the perpendicular legs of the four corner sections extensible. It is also obvious from an inspection of the drawings that the window screen shown in Figure 2 has been reduced in size transversely as well as vertically.

40 These hanger plates 19 and 20 on their adjacent ends have ears 26 provided with finger engaging openings 27 permitting of firm holds on the sections of the screen frame, for the purpose of adjustment.

45 Referring to Figure 7 it is obvious that the horizontal and perpendicular legs of the four corner sections of the inner screen frame are telescopically united to permit of extensibility as well as reduction of said inner screen frame. In 50 order to prevent entire disconnection telescopically of the four corner sections of the inner screen frame, certain walls of the horizontal and perpendicular legs of the four corner sections of the inner screen frame have registering slots 18a for the reception of headed two legged pins 18, the two legs of said pins passing through the 55 registering slots and being bent over in opposite directions at 18b shown in Figure 6, acting to retain the four corner sections of the inner screen frame in telescopic joined positions.

60 The lower rail of the outer frame of the screen frame is provided with a plurality of perforations

28 to permit the draining off of any water that may collect therein.

From the foregoing description together with the construction illustrated in the drawings it is obvious how the various corner sections of the inner and outer screen frames may be telescopically adjusted to reduce the size of the screen frame as well as rendering same extensible. Obviously from this construction, it is apparent that when adjusting the various sections of the screen frames it is necessary to have various areas of wire fabric screening in order to provide for the various adjustments.

It is obvious that by giving the screw eye hangers a partial or quarter turn so that the eyes 15 of said screw hangers will extend in alignment with the slots 21 and 22 of the hanger plates 19 and 21, it is possible to move the four corner sections of the outer screen frame, so as to remove the window screen from the window frame.

20 The invention having been set forth, what is claimed is:

1. In a screen frame, the combination with an outer frame comprising four telescopic frame sections, of an inner screen frame likewise comprising four telescopic corner sections, the corner sections of the inner screen frame provided with hollow rolled beads caused to telescope, an area of wire fabric screening with its edge portions rolled within certain of the hollow beads, 30 thereby mounting the screening, the opposed walls of the outer screen frame having hollow rolled beads to telescope and to impinge on the screening.

2. In a screen frame, the combination with an outer frame comprising four telescopic frame sections, of an inner screen frame likewise comprising four telescopic corner sections, the corner sections of the inner screen frame provided with hollow rolled beads caused to telescope, an 40 area of wire fabric screening with its edge portions rolled within certain of the hollow beads, thereby mounting the screening, the opposed walls of the outer screen frame having hollow rolled beads to telescope and to impinge on the 45 screening, and means to prevent slipping of the telescopic legs of the four corner sections of the outer screen frame.

3. In a screen frame, the combination with an outer frame comprising four telescopic frame sections, of an inner screen frame likewise comprising four telescopic corner sections, the corner sections of the inner screen frame provided with hollow rolled beads caused to telescope, an 50 area of wire fabric screening with its edge portions rolled within certain of the hollow beads, thereby mounting the screening, the opposed walls of the outer screen frame having hollow 55 rolled beads to telescope and to impinge on the screening.

60 HARRY ELI BAUMGARDNER.
